ATTORNEY.

UNITED STATES PATENT OFFICE.

CAMPBELL P. HIGGINS, OF BROOKLYN, NEW YORK.

STEAM-GENERATOR.

SPECIFICATION forming part of Letters Patent No. 364,348, dated June 7, 1887.

Application filed October 6, 1886. Serial No. 215,445. (No mod.)

To all whom it may concern:

Be it known that I, CAMPBELL P. HIGGINS, a citizen of the United States, residing at Brooklyn, in the county of Kings and State of New York, have invented a new and useful Improvement in Steam-Generators, of which the following is a specification, reference being had to the accompanying drawings, forming a part of the same, in which—

10 Figure 1 is a front view of a cross-header of a sectional steam-generator embodying my invention, and Fig. 2 a plan view of the same; Figs. 3, 4, and 5, a front, plan, and end view, respectively, of such a header in which an additional heating-tube is arranged.

15 The object of this invention is to obtain convenient access to the ends and interior of the heating-tubes for the purpose of introducing and operating an expanding-tool for securing 20 the tubes or a tool for scraping or cleaning the interior of the tubes.

The invention is shown in connection with a serpentine form of header embracing a series of heating tubes arranged in staggered 25 clusters of three or more, and having hand-holes with removable covers arranged with relation to each cluster of tubes so that the end of each tube is sufficiently exposed to the hand-hole opening for the purpose of securing and 30 cleaning and one or two fully exposed for removing direct, the next adjacent or partially-exposed tubes being also capable of subsequent removal through the fully-exposed openings, as hereinafter explained.

35 In the drawings, A represents the header; B, the hand-hole plate or cover; C, the yoke or clamp for holding the plate in place, and a, b, c, d, and e the heating-tubes.

In Fig. 1 of the drawings a cluster of three 40 heating-tubes is shown, the end of the tube a

being fully exposed to the hand-hole opening and the ends of the adjacent tubes b c but partially exposed. The tube a is capable of direct removal and the tubes b and c are removed or replaced indirectly through the aperture that contained the tubes a.

In Figs. 3 and 4 of the drawings clusters of four tubes each are shown, two of which, d and e, being capable of direct removal and the others capable of indirect removal or insertion through either of the fully-exposed apertures.

It will be observed that in the polygonal form of headers shown the width of the hand-hole opening is necessarily restricted, and but 55 one or two of the tubes clustered and staggered as shown can possibly be included in the direct line of the opening. It will also be observed that an additional amount of tube-heating surface can be connected to each 60 header, and as the header is the most expensive part of the structure, the greater the connected heating-surface the less will be the total cost.

Therefore, what I claim, and desire to secure 65 by Letters Patent, is—

A header for steam-generators of polygonal form in cross-section having a series of clusters of heating-tubes connected therewith, and provided with hand-hole openings located opposite the ends of said clusters of tubes, so that a portion is fully exposed to the hand-hole openings and the remaining portion partially exposed, whereby all the tubes composing the cluster may be cleaned, removed, or replaced, 75 as set forth.

CAMPBELL P. HIGGINS.
